CLAIM

The ornamental design for a liquid output regulator for drink making machine, as shown and described.

DESCRIPTION

FIG. 1 is a top, front, and right side perspective view showing my new design for a liquid output regulator for drink making machine;

FIG. 2 is a bottom, front, and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof;
